US00D818500S

(12) United States Design Patent (10) Patent No.: US D818,500 S
 Marianek et al. (45) Date of Patent: * May 22, 2018

(54) DISPLAY SCREEN OR PORTION THEREOF WITH ICON

(71) Applicant: Apple Inc., Cupertino, CA (US)

(72) Inventors: Joe Marianek, San Francisco, CA (US); Wan Si Wan, Sunnyvale, CA (US); Christopher Wilson, San Francisco, CA (US)

(73) Assignee: Apple Inc., Cupertino, CA (US)

() Term: 15 Years

(21) Appl. No.: 29/601,824

(22) Filed: Apr. 26, 2017

Related U.S. Application Data

(63) Continuation of application No. 29/585,614, filed on Nov. 28, 2016, now Pat. No. Des. 785,648, which is a continuation of application No. 29/565,199, filed on May 18, 2016, now Pat. No. Des. 772,940, which is a continuation of application No. 29/457,326, filed on Jun. 9, 2013, now Pat. No. Des. 757,737.
